D19678

UNITED STATES PATENT OFFICE.

WILLIAM W. GOODWIN, OF BORDENTOWN, NEW JERSEY.

DESIGN FOR A GAS-RANGE.

SPECIFICATION forming part of Design No. 19,678, dated March 4, 1890.

Application filed January 31, 1890. Serial No. 338,783. Term of patent 7 years.

To all whom it may concern:

Be it known that I, WILLIAM W. GOODWIN, a citizen of the United States, residing at Bordentown, Burlington county, State of New Jersey, have invented a certain new and Original Design for Gas-Ranges, of which the following is a full, clear, and exact description, reference being had to the accompanying drawings, forming a part of this specification.

My invention relates to gas-ranges; and it consists of the novel configuration thereof, as illustrated in the accompanying photograph, forming a part of this specification. The essential features thereof are the form of the whole structure as a parallelogram, the ar-

angement of the roasting-chambers relatively to each other and to the upper broiling-chamber, the gas-jets, and the external form, in its several features, of the doors of the roasting-chambers.

I claim—

The design for a gas-range, substantially as shown and described.

In testimony whereof I have hereunto affixed my signature this 5th day of December, A. D. 1889.

WILLIAM W. GOODWIN.

Witnesses:

ANDREW ZANE,
H. T. FENTON.
